UNITED STATES PATENT OFFICE.

SYDNEY E. SINCLAIR AND HENRY B. SOUTTER, OF CEDAR RAPIDS, IOWA.

DESIGN FOR A PINCUSHION.

SPECIFICATION forming part of Design No. 31,302, dated August 1, 1899.

Application filed July 10, 1899. Serial No. 723,424. Term of patent 7 years.

To all whom it may concern:

- Be it known that we, SYDNEY E. SINCLAIR, a subject of the Queen of Great Britain, and HENRY B. SOUTTER, a citizen of the United States, residing at Cedar Rapids, in the county of Linn and State of Iowa, have invented and produced a new and original Design for Pincushions, of which the following is a full and clear description.
- 10 In the accompanying drawings, forming a part of this specification, Figure 1 is a front or plan view of a pincushion, illustrating our new design. Fig. 2 is a side view of the same. The leading or material feature of the design is the general outline or contour given to the cushion, as shown in the drawings.
- 15 Referring to Fig. 1, the general outline is that of an approximate rectangle, but with all the corners curved and the lower end somewhat narrower than the upper end. The side from A to B is practically straight, as are also the ends, which are practically parallel. At the middle of the upper end is a loop C. The side from D to E forms a slight inward curve.
- 20 25 The figure is surrounded on all except the

straight side from A to B by a narrow margin F, having the appearance of a cord or overcast-seam.

As seen from the side and as shown in Fig. 2, the design shows a regular figure, with practically straight parallel sides, rounded ends, the upper one terminating in a loop, and a central longitudinal division having the appearance of a cord or overcast-seam.

The design is intended to simulate in a conventional manner a neatly-trimmed canvas-covered piece of bacon.

Having thus described our invention, what we claim as new, and desire to secure by Letters Patent, is—

The design for a pincushion as herein shown and described.

In testimony whereof we affix our signatures in presence of two witnesses.

SYDNEY E. SINCLAIR.
HENRY B. SOUTTER.
